US00D988260S

(12) **United States Design Patent** (10) Patent No.: **US D988,260 S**
 Sohn et al. (45) Date of Patent: ** Jun. 6, 2023

(54) **CHARGING CASE FOR WIRELESS
EARPHONES**

(71) Applicant: **Samsung Electronics Co., Ltd.**, Suwon-si (KR)

(72) Inventors: **Sangok Sohn**, Suwon-si (KR); **Yongseok Bang**, Suwon-si (KR); **Kwangha Choi**, Suwon-si (KR); **Jaehyung Hong**, Suwon-si (KR); **Youngsang Jang**, Suwon-si (KR); **Sangsun Woo**, Suwon-si (KR)

(73) Assignee: **SAMSUNG ELECTRONICS CO., LTD.**, Gyeonggi-Do (KR)

(**) Term: **15 Years**

(21) Appl. No.: **29/805,620**

(22) Filed: **Aug. 27, 2021**

(30) **Foreign Application Priority Data**

(57)

CLAIM

The ornamental design for a charging case for wireless earphones, as shown and described.

DESCRIPTION

FIG. 1 is a front perspective view of a charging case for wireless earphones showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom perspective view thereof.

The broken lines in the figures depict portions of a charging case for wireless earphones that form no part of the claimed design.

1 Claim, 5 Drawing Sheets
